UNITED STATES PATENT OFFICE.

ALBERT L. DAVIS, OF NORWALK, OHIO.

VAULT-LOCK.

1,375,134.

Specification of Letters Patent. Patented Apr. 19, 1921.

Application filed November 15, 1919. Serial No. 338,176.

To all whom it may concern:

Be it known that I, ALBERT L. DAVIS, a citizen of the United States, residing at Norwalk, in the county of Huron and State of Ohio, have invented certain new and useful Improvements in Vault-Locks, of which the following is a specification.

This invention relates to closures for burial vaults, and the primary object of the invention is the provision of an improved means for locking and sealing the closure in position against accidental displacement.

Another object of the invention is the provision of an improved lock for vault closures, which is so constructed that operation thereof is prevented after the door has been placed in closed position and locked.

A further object of the invention is the provision of novel means for moving the connecting means of the lock bolts out of engagement with the bolt operating means, after such means have been operated to move the bolts to locked position.

A still further object of the invention is the provision of means for preventing retrograde movement of the bolt actuating means so as to absolutely prevent the unlocking of the closure.

A still further object of the invention is the provision of an improved grave vault lock, of the above character which is durable and efficient in use, one that is simple and easy to manufacture, and one which can be placed upon the market at a reasonable cost.

Other objects of the invention will appear in the following detailed description taken in connection with the accompanying drawings, forming a part of this specification, and in which drawings:

Figure 1 is a rear elevation of the improved vault seal and lock, showing the same in operative position on a vault, the vault being shown in section.

Fig. 2 is a central vertical section through the vault closure and lock, showing the bolts in locked position prior to being moved into inoperative position against further action.

Fig. 3 is a similar view showing the bolts moved into inoperative position and locked against further actuation.

Fig. 4 is an enlarged section taken on the line 4—4 of Fig. 3.

Fig. 5 is a detail perspective view of one of the bolts, and

Fig. 6 is a fragmentary detail side elevation of the bolt guide disk showing the same in locked position.

Referring to the drawings, in detail, wherein similar reference characters designate corresponding parts, throughout the several views, the letter A indicates the improved vault closure, which is adapted to be associated with a vault B. The improved vault closure or lock includes the bolts C, the bolt actuating mechanism D and the lock E for the actuating member D.

The vault B may be of the ordinary or any preferred construction and formed of any suitable material and as shown includes the upper and lower walls 10 and 11, and the side walls 12. The open end of the vault has secured to the upper, lower and side walls adjacent to the outer end thereof, strips of angle iron 13, which form a means for limiting the inward movement of the vault closure A. In the space between the closure A and the strips of angled iron 13 is a gasket formed of rubber or the like 14, which forms means to seal the vault when the vault closure is in its locked position.

The approved door closure and lock A includes a flat door plate 15 formed of metal or the like and suitably shaped so as to fit snugly within the vault. The door plate 15 is secured to the upper wall 10 of the vault by a suitable hinge 16.

The door plate 15 has slidably mounted on the inner surface thereof the bolts C which are substantially triangular shaped in plan and formed from flat metallic plates, as clearly shown in Fig. 5 of the drawings. The outer edge of each of the bolts C is provided with inwardly extending slots 18, which slidably receive the T-shaped studs 19 riveted or otherwise secured to the door plate 15 adjacent to the outer edges thereof.

The inner ends of the bolts C are provided with slots 20, which are arranged parallel to the slots 18 formed in the outer side edges of the bolts C. The door plate 15 has also

riveted or otherwise secured thereto adjacent the central portion thereof the inwardly extending guide pins 21 which are slidably received in the slots 20. The guide pins 21 have coiled around the same the expansion springs 22, which are confined between the door plate 15 and the bolts C, and form means for normally urging the inner ends of the bolts C outwardly.

10 The pins 21 and the T-shaped studs 19 form means for permitting the sliding movement of the bolts C toward or away from the outer edges of the vault. The actuating mechanism D is provided for 15 moving the bolts C into or out of engagement with the outer surface of the strips or angle iron 13, and includes a shaft 23, which is rotatably mounted in a centrally located aperture formed in the door plate 15. The 20 shaft 23 is provided with an enlarged smooth portion 24 and has keyed or otherwise secured thereto the operating disk 25, which engages the inner face of the door plate 15. The outer face of the door plate 25 15 is engaged by a flat annular flange 26 formed on the shaft and the same forms in connection with the disk 25 the means for preventing twisting or swinging movement in the aperture. The extreme outer end of 30 the shaft 23 is provided with a polygonal extension 27, which forms means whereby the shaft may be engaged by a suitable tool to effect the rotation thereof. Inward movement of the disk 25 on the shaft 23 is 35 prevented by an annular flange 28 formed on the shaft 23. The shaft 23 is continued inwardly of the door plate 15 and the portion of the same lying beyond the flange 28 is provided with screw threads 29 for a 40 purpose which will be hereinafter more fully described. This portion of the shaft is also provided with an inwardly extending slot 30 which terminates short of the screw threaded portion. The inner terminals of 45 the bolts C at the apex portion thereof carry pins 31 which project inwardly toward the door plate 15.

The pins are provided with annular flanges 32 which prevent inward movement 50 of the same on the bolts C. The inner face of the operating disk 25 is provided with a spiral or cam slot 33, the outer convolution of which is formed substantially concentric with the shaft 23. The slot 33 is adapted to 55 receive the inner terminals of the pins 31, so that upon rotation of the disk, the bolts C will be brought toward or away from the angle irons 13 as may be desired.

The outer ends of the pins 31 are provided 60 with enlarged extensions 35 carrying T-heads 36, the purpose of which will be hereinafter more fully described.

The means F provided for locking the 65 actuating mechanism against further operation when the bolts C are in locked position

includes a circular plate 37 which is provided with a central internally threaded bore 38 which is adapted to be threaded on the threaded portion 29 of the shaft 23. The circular plate 37 is provided at equidistantly spaced points with vertically extending slots 39, which slidably receive the extensions 35 of the pins 31 and the T-heads 36 thereof engage the outer surfaces of the plate. The pins 31 prevent rotation of the 75 plate 37 on the shaft 23. The slot 30 formed in the threaded portion 29 of the shaft 23 has slidably mounted therein the pawl 40, which has the terminals thereof provided with opposite directed teeth 41, 80 which are adapted to engage upstanding lugs 42, having the upper faces inclined downwardly as at 43 so as to permit the pawl to slide over the same when rotated in one direction. The pawl 40 is held in engagement with the inner wall of the slot 30 by means of an expansion spring 44, which is coiled around the shaft and has the inner end thereof in engagement with the outer surface of the pawl. The coiled spring 44 90 is prevented from slipping off of the shaft by means of the nut 45 which also forms means for adjusting the tension of the spring 44. The inner faces of the bolts C adjacent to the outer edge thereof are provided with inwardly extending lugs 46, which form means for engaging the inner surface of the door plate 15 for holding the bolts in spaced relation thereto.

In operation of the improved device, when 100 it is desired to lock the door, a suitable tool such as a wrench or the like is clamped upon the polygonal extension 27, and the shaft 23 is then rotated, which owing to the spiral or cam slot 33 having the pins 31 slidably mounted therein, forces the bolts C outwardly and into engagement with the outer surface of the angle irons 13, and thus prevents outward movement of the door plate. As the shaft 23 is rotated, the plate 37 is 105 gradually threaded outwardly on the threaded portions 29 of the shaft, which gradually brings the pins 31 toward the outer end of the spiral or cam groove 33. When the bolts C are in their locked positions, the 110 pins 31 have been moved out of the slots 33. When it is desired to position the lock mechanism so that operation thereof is prevented, the shaft 23 is further rotated so as to move the circular plate 37 outwardly on 115 the shaft 23, which will carry the pins 31 out of engagement with the spiral or cam groove formed in the disk. As the circular plate 37 gradually moves outwardly on the shaft 23, the expansion spring 44 is gradually compressed, which tensions the same so that the double pawl 40 is forcibly held into contact with the outer face of the plate 37. As the shaft is rotated in a direction to move the plate 37 outwardly, the beveled 120

125

130

lugs 42 permit the double pawl to slide over the beveled face 43 of the same, but when the shaft is turned in a reverse direction, so as to move the tumbler plates inwardly, the 5 double pawls 40 engage the abrupt faces of the lugs 42 and thus prevent rotation of the plate. This effectively prevents operation of the lock to move the bolts C out of engagement with the angle irons 13 and thus 10 the door is permanently held in its closed position.

From the foregoing description it will be seen that the improved vault door lock is provided which is so constructed that the 15 door cannot be opened after once being placed in position or locked in place.

Changes in details may be made without departing from the spirit or scope of my invention, but;

20 I claim:

1. The combination with a body having one end thereof opened, and a closure head for said opened end, of locking mechanisms carried by the closure head and including 25 a plurality of radially extending bolts slidably mounted on the head, an actuating element, means carried by the bolts for engaging said element, and means for moving said bolt engaging means out of engagement 30 with said actuating means, when the bolts have been moved into locked position.

2. The combination with a body having an opened end and a closure head for said opened end, of locking mechanisms carried 35 by the closure head including a plurality of bolts slidably carried by the head, a rotatable disk carried by the head, means for effecting the rotation of the disk, said disk having a spiral slot formed in its inner 40 face, means carried by the inner ends of the bolts, for engaging in said slots, and means for moving said bolt carried means out of engagement with the disk, after the bolts have been moved to locked position.

45 3. The combination with a body having one end thereof opened, and a closure head therefor, of locking mechanism carried by the closure head including a plurality of slidable bolts mounted on the head, a shaft 50 rotatably carried by the head, an actuating member keyed to the shaft, pins carried by the inner ends of the bolts and adapted to engage the actuating member for moving the bolts into closed position, and means 55 carried by said shaft for moving the pins out of engagement with the actuating means, after the bolts have been moved to locked position.

60 4. The combination with a vault body and closure head therefor, of locking mechanism carried by the closure head and including a plurality of bolts slidably carried by the head, a shaft rotatably carried by the head, means for rotating the shaft, a disk keyed 65 to the shaft having a spiral slot formed

therein, pins carried by the inner ends of the bolts and adapted to engage in the spiral slot, so that upon rotation of the disk in one direction, the bolts will be moved outwardly, and means carried by said shaft for 70 engaging the pins to move the same out of engagement with the spiral slots, after the bolts have been moved to locked position.

5. The combination with a body having an opened end and a closure head therefor, 75 of a locking mechanism carried by the closure head including a plurality of bolts, actuating mechanism carried by said head, means carried by the inner ends of the bolts for engaging said actuating means, a plate 80 carried by the shaft for engaging said bolt carried means and adapted to move the same out of engagement with the actuating means when the bolts have been moved to closed position, and means to prevent movement 85 of the plate in one direction after the bolt carried means have been moved out of engagement with the actuating means.

6. The combination with a vault body and closure head therefor, of a locking mechanism carried by the closure head including a plurality of slidable bolts carried by the head, a shaft rotatably carried by the head, a disk keyed to the shaft and having a cam slot formed therein, pins carried by the 90 inner ends of the bolts and arranged to engage in said cam slot, a locking plate threaded on said shaft arranged to carry said pins, a pawl carried by the shaft, and outwardly extending teeth formed on the 100 outer face of the plate and adapted to be engaged by the pawl.

7. The combination with a vault body and closure head therefor, of a locking mechanism carried by the closure head including 105 a plurality of slidable bolts, guide pins for said bolts, springs coiled around certain of said pins for normally urging the inner ends of the bolts inwardly, a shaft rotatably carried by the head, a disk keyed to the shaft 110 having a spiral groove formed on the inner face thereof, the outer convolution of the groove being arranged concentric with the axis of the disk, pins carried by the inner ends of the bolts arranged to engage in said 115 groove, and a plate threadably mounted on said shaft for carrying said pins, outwardly extending teeth formed on the outer face of the plate, a double ended pawl slidably carried by the shaft, and spring means for 120 normally urging the pawl into engagement with the teeth.

8. A lock comprising a plurality of bolts, a cam, means carried by the bolts for engaging the cam, said means arranged to move 125 the bolts to a locked position when the cam is operated, and automatic means for moving said bolt carried means out of engagement with the cam when the bolts have been moved to a locked position.

9. A lock comprising a plurality of bolts, a cam disk, means carried by the bolts for engaging said cam disk, said means arranged to move the bolts to a locked position when the cam disk is operated, means for moving said bolt carried means out of engagement with the cam disk when the

bolts have been moved to a locked position, and means for preventing movement of said means for moving the bolt carried means 10 out of engagement with the cam after the bolts have been moved to locked position.

ALBERT L. DAVIS.
